UNITED STATES PATENT OFFICE

2,549,602

APPLICATOR FOR ION TRAPS

Lewis Hopps, Darien, Conn., assignor to The Indiana Steel Products Company, Chicago, Ill., a corporation of Illinois

Application October 1, 1949, Serial No. 119,132

1 Claim. (Cl. 250—161)

1

This invention relates to means for applying resiliently clamped assemblies to the neck portions of cathode ray tubes, and more particularly to a device which facilitates application of field structures of ion traps to the neck portions of cathode ray tubes.

Field structure assemblies for ion traps of television cathode ray tubes have heretofore usually been of the type which could be clamped about the neck of the cathode ray tubes by means of a clamping assembly secured by some form of nut and bolt arrangement which also provided means for adjusting the clamping forces on the tube neck. Another and more recent type of field structure assembly utilizes a resilient clamping means which may be slipped over the end of the tube neck and slid into the desired position thereon. One form of the latter type of assembly is described in greater detail in a copending application in which I am a co-inventor with Philip A. Smith entitled "Ion Trap and Centering Magnet Assembly," Serial No. 119,133, filed October 1, 1949. This type of field structure assembly utilizes clamping means of spring material capable of being resiliently expanded as the structure is slipped into position on the outer periphery of the member on which it is to be clamped. Thus in mounting the field structure on a cathode ray tube, it is preferable that means be provided that are operative during the mounting operation to facilitate the slipping of the assembly over the socket and onto the neck of the tube.

It is, therefore, a particular object of the present invention to provide a novel and simple means for facilitating the mounting of spring clamp type ion trap field structures on cathode ray tubes.

Still another object of the present invention is to provide novel means for mounting spring clamp type ion trap field structures on cathode ray tubes for television sets, which means will also insure that the plug ends of such tubes will not be damaged during the mounting operation.

Another and still further object of the present invention is to provide a novel means for mounting ion trap field structures on cathode ray tubes of television sets which means will be both simple in construction and also readily adaptable to production assembly operations.

A still further object of the present invention is to provide a novel unitary device which will both protect the plug end of the television cathode ray tube during the operation of mounting a spring clamp assembly on the neck of the tube

2

and which will at the same time provide a simple means whereby the assembly may be slipped over the plug and onto the tube neck to the position desired.

5 The novel features which are believed to be characteristic of my invention are set forth with particularity in the appended claims. My invention, however, as to its organization and method of operation, together with further objects and advantages thereof may best be understood by reference to the following description taken in connection with the accompanying drawings in which:

Figure 1 is a side elevational view of a conventional type of cathode ray tube illustrating in full and dotted lines the operation of mounting an ion trap field structure thereon with the aid of an applicator embodying the principles of the present invention;

15 Figure 2 is a perspective view of an applicator embodying the principles of the present invention;

Figure 3 is a fragmentary side elevational view of the assembly of the ion trap applicator on the end of a cathode ray tube plug preparatory to mounting an ion trap field structure on said tube;

20 Figure 4 is an enlarged sectional view taken along the line IV—IV of Figure 1;

Figure 5 is a plan view of the open end of the ion trap applicator; and

25 Figure 6 is a plan view of the closed end of the ion trap applicator.

As shown on the drawings:

Figure 1 illustrates somewhat diagrammatically a cathode ray tube 10 while an ion trap assembly 11 is being mounted thereon by using an ion trap applicator 12 of the present invention. The cathode ray tube 10 is of a type in general use for television reception purposes having an enlarged bulbular fan-shaped portion on which a viewing screen 13 is provided while the remainder of the tube comprises a relatively long narrow tubular neck portion 14 which encloses an electron gun 15. The narrow neck portion 14 terminates in a tube plug 16 of the same diameter as the tube neck and to which electrical connections of the inner tube elements are made. A plurality of prongs 18 of relatively short length project from the face of the plug 16, and the electrical elements within the tube are connected thereto so that connections may be made between the inner elements and external apparatus.

30 One type of spring clamp assembly 11 which may be mounted by means of the applicator 12

of the present invention, as mentioned above, is described fully in a co-pending application entitled "Ion Trap and Centering Magnet Assembly" Serial No. 119,133, filed October 1, 1949 for which I am a co-inventor with Philip A. Smith. This ion trap assembly 11 comprises a pair of ring-shaped magnets 20 and 21 which are held by a one-piece split spring-like clamping support member 22. The spring-like clamping support member 22 is made of thin flat nonmagnetic material, such as brass in the general form of an equilateral triangle. Notches are provided on each corner of the support to provide means for holding the ring magnets 20 and 21. The triangular member 22 is normally not sufficiently large to enable it to be slipped over the plug 16 and onto the neck 14 of the cathode ray tube 10 but for that purpose it is capable of being spread or expanded within the ring magnets 20 and 21. The sides of the triangle then become substantially bow-shaped, and the cross-sectional area bounded by the sides of the triangle becomes large enough for the assembly to be slipped over the plug 16 and onto the tube neck 14.

Without the use of an applicator, as shown, the operation of expanding the resilient ring support member and at the same time carefully slipping the assembly over the tube socket and neck, to avoid damaging the tube plug and its prongs 18, would be a very cumbersome and time consuming operation and obviously does not readily lead itself to production assembly operations.

By utilizing an applicator 12, however, which is best shown in perspective in Figure 2, spring clamp assemblies such as ion trap field structure assemblies may very easily be mounted on the necks of cathode ray tubes, and at the same time, the prongs of the plugs thereof will be protected from damage. The applicator 12 is preferably made of light material, such as aluminum, and is tapered along its length to provide a frustoconical shape so that the spring support member 22 of the assembly 11 will expand as it is pushed thereover from the smaller end 26 towards the larger end 27. The larger end of the applicator has the same outside diameter as the tube base or plug 16 with which it is associated. A cylindrical recess 24 of a depth slightly greater than the length of the prongs 18 is concentrically provided in the face of the larger end 27 of the applicator and has a diameter such that the applicator will fit snugly over the prongs 18 which define a circular pattern in the base of the plug 16. The smaller end 26 of the applicator 12 has an outside diameter less than that of the opening defined of support member 22 in its normal, unexpanded state.

Thus, when the applicator 12 is slipped over the prongs 18 in the manner shown in Figure 3, the ion trap assembly 11 may be mounted on the tube neck 14 by merely slipping it over the smaller end 26 of the applicator 12 and pushing it toward the larger end 27 thereof until it reaches and surrounds the socket 16 from which the assembly may be further slid onto the neck 14 to any desired position along the neck, such as the position in which it is shown in the dot-dash lines of Figure 1. It is apparent that after the

assembly has been mounted in the desired position, the applicator 12 may be removed for use on other tubes.

The applicator may also be used in another way in view of the provision of the cylindrical shoulder portion 25 thereon at the largest end 27 thereof. The untapered portion 25 has the same diameter as the socket 16, and may be utilized to expand and hold the spring support member 22 in its expanded relation until the applicator is inserted over the prongs 18. In other words, the applicator 12 need not be inserted over the prongs 18 before the assembly 11 is expanded, but may be separately utilized to first expand the spring member 22 to the size which will enable it to be slipped directly onto the plug 16.

It will be apparent to those skilled in the art that the applicator which I have described for use in mounting ion trap assemblies on the necks of cathode ray tubes, is not necessarily limited to use in mounting ion trap assemblies alone but that almost any form of spring clamp assemblies which is to be mounted in surrounding relation on the necks of such tubes may be mounted with great ease by use of the applicator which I have described.

While I have shown and described a particular embodiment of my invention, it will, of course, be understood that I do not wish to be limited thereto since many modifications may be made, and I, therefore, contemplate by the appended claim to cover all such modifications that fall within the true spirit and scope of my invention.

I claim as my invention:

An applicator for mounting spring supported assemblies on the neck of a cathode ray tube having circularly arranged contact prongs, said applicator comprising a one-piece member having frustoconical wall portion and a joining cylindrical wall portion extending from the larger diameter end of said frustoconical portion, there being a cylindrical recess concentric with said cylindrical wall portion in the adjacent end of said member of such depth and diameter as to snugly receive the prongs of said tube.

LEWIS HOPPS.
